(57) CLAIM

The ornamental design for a display screen with graphical user interface, as shown and described.

DESCRIPTION

FIG. 1 is a front view of a display screen with graphical user interface; and,

FIG. 2 is a second embodiment thereof.

The broken lines showing portions of the display screen with graphical user interface form no part of the claimed design.

1 Claim, 2 Drawing Sheets

Find the Plan That Best Fits You

100%

WHAT ARE YOUR PLAN PREFERENCES?

Cost is an important factor when choosing a health plan, but not the only one.

What's more important:

LOW COST vs FINANCIAL RISK

I strongly prefer LOW COST

I prefer the plan with the lowest cost in a year of my typical medical needs.

I strongly prefer LOW COST

I want the plan with the lowest cost in a year of my typical medical needs.

LOW COST vs BROADER PROVIDER ACCESS

I strongly prefer LOW COST

I want the plan with the lowest cost in a year of my typical medical needs.

I strongly prefer LOW COST

I want to pay more for broader access and less restrictions when using medical needs.

Showing Your
TOP 3 PLANS:

1st Heartland Value Network HMO

ESTIMATED YEARLY COSTS
$4,289

2nd Freedom Choice high deductible with HSA

ESTIMATED YEARLY COSTS
$3,300

3rd Heartland Open Access EPO

ESTIMATED YEARLY COSTS
$5,300

WHAT ARE YOUR PLAN PREFERENCES?
Cost is an important factor when choosing a health plan, but not the only one.

What's more important:
LOW COST vs BROADER PROVIDER ACCESS

I strongly prefer LOW COST
I want the plan with the lowest cost in a year of my typical medical needs.

I have no preference
NEUTRAL

I strongly prefer BROADER PROVIDER ACCESS
I want to pay more for broader access and less restrictions when using medical needs.

What's more important:
LOW COST vs FINANCIAL RISK

I strongly prefer LOW COST
I want the plan with the lowest cost in a year of my typical medical needs.

I have no preference
NEUTRAL

I strongly prefer LOW FINANCIAL RISK
I want to pay more overall to be shielded from large medical bills in case of high medical needs.
